UNITED STATES PATENT OFFICE

2,329,443

OVERHEAD DOOR CONSTRUCTION

Alvin V. Rowe, Galesburg, Ill., assignor to Rowe Manufacturing Company, Galesburg, Ill., a corporation of Illinois

Application December 19, 1941, Serial No. 423,655

8 Claims (Cl. 160—209)

This invention relates generally to overhead door constructions, and more particularly to those features of construction which facilitate the guiding of a plurality of hingedly connected door sections between closed vertical position and open overhead position.

The invention is particularly concerned with the provision of door guiding structural features which will enable installation in instances where a relatively small space above the door opening is available.

To enable installation where a relatively small space is available above the door opening, it is proposed to provide improved, simplified means for positively preventing the upper and lower margins of the door from swinging away from the guideway. To this end the invention contemplates a simplified and improved curved guideway or track structure in combination with a novel guide roller arrangement associated with the upper and lower margin of the door.

It is also an object of the present invention to provide the aforesaid advantages without necessitating the use of expensive, specially designed vertical and horizontal track structures.

It is also contemplated that the novel features referred to above may be used in combination with door guiding means, such as guide tracks equipped with switch mechanisms of the type illustrated in my recently issued Patents 2,264,642 and 2,264,643 relating to Overhead door constructions.

The foregoing and other objects and advantages will be more apparent from the following detailed description when considered in connection with the accompanying drawings, wherein—

Figure 1 is a vertical sectional view taken substantially along the line 1—1 of Figure 2, disclosing the present invention in association with a plurality of hingedly connected door panels which occupy a vertical closed position;

Figure 2 is a vertical sectional view taken substantially along the line 2—2 of Figure 1;

Figure 3 is an enlarged, fragmentary vertical sectional view similar to the disclosure in the upper left hand corner of Figure 1 to more clearly illustrate the structural details and functional relationship of the elements contemplated by the present invention;

Figure 4 is a fragmentary vertical sectional view taken substantially along the line 4—4 of Figure 3 to more clearly disclose the structural arrangement of the curved auxiliary guideway and elements located in the vicinity thereof;

Figure 5 is an enlarged horizontal sectional

view taken substantially along the line 5—5 of Figure 3 to more clearly illustrate the cooperative relationship between double guide roller construction carried by the uppermost panel and the auxiliary curved guide track as contemplated by the present invention; and

Figure 6 is a fragmentary elevational view of the lower bracket and guide rollers carried thereby, as viewed along the line 6—6 of Figure 3.

Referring now to the drawings more in detail wherein like numerals have been employed to designate similar parts throughout the various figures, it will be seen that, for purposes of illustration, the invention contemplated hereby has been shown in operative association with a series of door sections designated by the letters A, B, C and D, respectively. These sections are hingedly connected by identical hinge mechanisms positioned along the outer margins of the sections and designated generally by the numeral 10. Inasmuch as the present invention does not specifically concern the structural details of these hinges, it will suffice to say that these hinges not only serve to hingedly or pivotally connect the panels, but also serve as a support for guide rollers 12 hereinafter referred to as the intermediate guide rollers. Particular attention is directed to the fact that these intermediate guide rollers are guided by and move within a guide track arrangement comprising an upright or vertical guideway portion 14, a curved or intermediate guideway portion 16, and an overhead substantially horizontal guideway portion 18. These intermediate guide rollers 12 are free to move within the aforesaid guideways 14—16—18 as the door sections A—B—C—D shift between closed vertical position and open overhead position.

In the vicinity of the lower extremity of the curved guideway portion 16 and the upper extremity of the vertical guideway 14, I provide a switch mechanism designated generally by the numeral 20; and a similar switch mechanism designated generally by the numeral 22 is provided in the vicinity of the upper extremity of the curved guideway 16 and the forward extremity of the horizontal guideway portion 18. A detailed description of these switch mechanisms is not essential for a clear understanding of the present invention, and it will suffice to say that these switch mechanisms correspond structurally with those disclosed in my aforesaid recently issued United States Patent No. 2,264,643. Sufficient structure of these switch mechanisms 20 and 22 will be referred to for a clear understanding of the function thereof. The switch mechanism 22

serves to selectively control connection or communication of the horizontal track portion 18 with the curved track portion 16 and an auxiliary curved track portion 24. This track portion 24 is suitably secured to a frame or gusset plate 26 and in transverse cross-section appears as shown in Figures 4 and 5. The switch mechanism 20 serves to selectively control connection or communication of the vertical guideway 14 with the curved track or guideway portion 16 and the aforesaid auxiliary section 24.

The present invention particularly concerns the structural and functional arrangement of the elements referred to above in combination with a pair of lower roller-bracket devices designated generally by the numeral 28 and a pair of upper roller-bracket devices designated generally by the numeral 30. The lower roller-bracket devices 28 are secured as by means of suitable fastening means or bolts 32 (Figure 6) to the lower corner portions of the lower door section A, whereas each of the roller-bracket devices 30 is secured to the upper panel D in opposite corners thereof as by means of suitable fastening elements or bolts 34 (Figure 5). The device 28 consists of a bracket member 36 and a pair of horizontally disposed shafts 38 and 40, which at one end support rotary follower members 42 and 44, respectively. The roller 44 is of conventional design and as the door section A moves within the vertical guideway portion 14 the roller 44 is guided within said section. Extending axially beyond the roller 44 is a projection 46 which is designed to engage the switch mechanism 20, in a manner later to be described, as the lower margin of the door section A approaches the curved guideway portion 16. The follower member or roller 42 is of special design, and is in the form of a disc member which is axially offset with respect to the roller 44, as illustrated in Figure 6, so as to clear the inside surface of the track or guideway 14. The peripheral surface of the follower member 42 is designed to engage a flange or lip 48 formed integral with and extending inwardly from a U-shaped portion 50 of the auxiliary curved track section 24 (Figure 5). The functional significance of the roller 42 and the auxiliary curved track section 24 will be more apparent from the description which follows.

The roller-bracket device 30 is structurally similar to the roller-bracket 28 just described, in that it incorporates a bracket member 52 which carries a pair of shafts 54 and 56. These shafts 54 and 56 are secured together so as to prevent relative axial movement by means of a connecting link 58 and in this connection it will be noted that the previously mentioned shafts 38 and 40 are similarly connected by a link 60. The outer extremities of the shafts 54 and 56 support rotary follower members 62 and 64, respectively, which correspond structurally with the rollers or follower members 42 and 44 previously described. Extending axially beyond the roller 64 is a projection 66 designed for engagement with the switch mechanism 22. It will be noted from the relative positions of the rollers 62 and 64, as shown in Figure 5, that the roller 64 is designed to follow within and be guided by the U-shaped portion 50 of the auxiliary curved guideway 24 and the roller 62 is designed for engagement with the flange or lip 48 as the upper door section D is shifted between vertical and horizontal position. That is to say, any tendency for the upper door section to swing outwardly away from the auxiliary guide-

way 24 is averted by the engagement of the roller 62 with the flange 48.

Upward movement to the door sections A-B-C-D from the vertical closed position shown in the drawings may be effected through the agency of spring-urged drums 68 or other suitable means positioned at each side and above the door sections, as clearly illustrated in the drawings. These drums 68 and their associated coiled springs 70 are carried on a suitable shaft 72 supported at one extremity within a frame 74 positioned above the gusset plate 26. A lifting cable 76 extends around the periphery of the drum 68 and thence downwardly to a bracket 78 (Figures 3 and 5).

As the door sections A-B-C-D move upwardly from their vertical closed position shown in the drawings, the rollers 44 of the roller-brackets 28 are guided within the upright or vertical guideway portions 14. Simultaneously the rollers of the roller-bracket 30 move along and are guided by the auxiliary curved track section or guideway 24. The sudden upward shifting of the door sections causes the panel D to experience a tendency to swing outwardly and this is positively prevented by the engagement of the rollers 62 with their companion track flange 48. The auxiliary guideway 24 directs the upper margin of the door section D upwardly and rearwardly until the roller 64 moves into engagement with a channel-like link or member 80 of the switch mechanism 22. As a result this channel member 80 is forced downwardly and thus communication or connection is established between the auxiliary guideway 24 and the horizontal guide section 18. The guide roller 64 continues rearwardly along the horizontal guideway 18 until the door reaches its full open position. A suitable spring 82 serves to continuously urge the switch link 80 and its companion link member 84 upwardly to the position shown in Figures 1 and 3 so that when the guide roller 64 moves rearwardly beyond the channel-like link member 80 and its associated link member 84, these members swing upwardly to the position shown in Figures 1 and 3, thus re-establishing communication between the curved guideway portion 16 and the horizontal guideway portion 18.

The intermediate follower members or rollers 12 associated with the hinges 10 move within the curved guideway portion 16 and thence into the horizontal guideway 18. As the roller-bracket devices 28 approach their respective switch mechanisms 20, the projection 46 associated with the roller 44 engages a switch arm or link member 86. This causes the link 86 and its associated channel-like link 88 to swing to the right, (Figures 1 and 3), thereby directing the roller 44 into the channel-like link member 88 and thence upwardly into the U-shaped portion 50 of the auxiliary curved track or guideway portion 24. Similarly to the upper margin of the door section D, previously described, the lower margin of the door section A experiences a tendency to swing outwardly away from the auxiliary guideway 24 as the door sections approach their completed open overhead position. This is prevented, however, by the engagement of the roller members 42 with companion flanges 48 of the curved auxiliary guideway 24. A suitable spring 90 associated with the pivoted extremity of the channel-like link member 88 serves to continuously urge the link members 86 and 88 to the left, as shown in Figures 1 and 3. Thus, when the roller 44 clears the link member 88 in its

upward movement, said link members shift to the left.

As the door sections experience reverse movement, namely, from their open overhead position toward their closed vertical position, the rollers 42 and 62 again serve to prevent outward swinging of the door section upon which they are mounted, and as each roller 44 of the door section A approaches its companion switch mechanism 20, said roller engages the channel-like link member 88, thereby establishing connection between the auxiliary guideway 24 and the vertical guideway 14. As the roller 44 clears the channel-like link member 88, communication or connection is again established between the vertical guideway 14 and the curved guideway portion 16, thus causing the intermediate guide rollers 12 to be directed from the curved guideway 16 into the vertical guideway 14. The projection 66 associated with the roller 64 eventually moves into engagement with the upper surface of the link member 84, thus causing the downward movement of this member and its associated channel-like link member 80. The roller 64 is in this manner directed from the horizontal guideway 18 along the channel-like link member 80 and thence within the auxiliary curved guideway 24.

From the foregoing it will be apparent that my invention contemplates a very practical and simplified guideway and control arrangement for overhead door sections. The novel and efficiently operable roller-bracket devices cooperate to insure smooth door operation and positively prevent any outward swinging of the upper or lower door section as they move along the upper curved auxiliary guideway. This precludes interference of the upper and lower door margins with the drum operating structure positioned immediately above the auxiliary guideway. In this manner the head room required for installation of the door construction is reduced to a minimum. Particular attention is directed to the novel construction of the auxiliary curved track or guideway sections wherein a U-shaped channel portion is provided for the main guide roller and an intermediately positioned guide track or flange is provided for a second or auxiliary roller. This construction eliminates the necessity of providing the conventional relatively wide curved guide track, as, for example, the conventional curved guide track section 16 employing an intermediate web and a pair of flanges projecting from each margin of said web. In fact, applicant's auxiliary curved guide track eliminates the necessity of using the conventional straight or flat flange extending from the web by employing a flange which extends outwardly from a U-shaped or channel-like track section. This is made possible by having the rollers of each roller-bracket shift along a path which is out of alignment with the path of movement of the other roller.

Obviously, modifications may be made without departing from the spirit and scope of the appended claims.

The invention is hereby claimed as follows:

1. In combination with a plurality of hingedly connected door sections presenting a door structure, intermediate track follower members carried in the vicinity of the hinged portions of said sections, and guideways positioned at opposite sides of said door sections for accommodating said follower members, said guideways comprising upright, curved and horizontal sections, an auxiliary curved guideway for connection with and extending upwardly from said upright

guideway, a pair of adjacently positioned follower members carried at the lower margin of said door structure, and adapted to be guided by and engage opposite sides of said auxiliary guideway at least one of said follower members being shiftable within the vertical guideway which guides the intermediate follower members, and means operable as an incident to the shifting of the door sections for controlling the operative association of said adjacently positioned follower members with said auxiliary guideway.

2. In combination with a plurality of hingedly connected door sections presenting a door structure, intermediate track follower members carried in the vicinity of the hinged portions of said sections, and guideways positioned at opposite sides of said door sections for accommodating said follower members, said guideways comprising upright, curved and horizontal sections, an auxiliary curved guideway for connection with and extending forwardly and downwardly from said horizontal guideway, a pair of adjacently positioned follower members carried at the upper margin of said door structure and adapted to be guided by and engage opposite sides of said auxiliary guideway, at least one of said follower members being shiftable within the horizontal guideway which guides the intermediate follower members, and means operable as an incident to the shifting of the door sections for controlling the operative association of said adjacently positioned follower members with said auxiliary guideway.

3. In combination with a plurality of hingedly connected door sections presenting a door structure, intermediate track follower members carried in the vicinity of the hinged portions of said sections, and guideways positioned at opposite sides of said door sections for accommodating said follower members, said guideways comprising upright, curved and horizontal sections, an auxiliary curved guideway for connection with said vertical and horizontal guideways and having a smaller curvature than the first mentioned curved guideway, a pair of adjacently positioned follower members at the lower margin of the door structure and adapted to be guided by and engage opposite sides of said auxiliary guideway, a pair of adjacently positioned follower members carried at the upper margin of said door structure and adapted to be guided by and engage opposite sides of said auxiliary guideway, and means operable as an incident to the shifting of the door sections for controlling the operative association of said pairs of adjacently positioned follower members with said auxiliary guideway.

4. In combination with a plurality of hingedly connected door sections presenting a door structure, intermediate track follower members carried in the vicinity of the hinged portions of said sections, and guideways positioned at opposite sides of said door sections for accommodating said follower members, said guideways comprising upright, curved and horizontal sections, an auxiliary curved guideway of smaller curvature than and positioned outwardly from the first mentioned curved guideway section, a pair of adjacently positioned follower members carried at at least one margin of said door structure and adapted to be guided by and engage opposite sides of said auxiliary guideway, one of said follower members being shiftable within the first mentioned upright guideway section which guides the intermediate follower members, and means operable as an incident to the shift-

ing of the door sections for controlling the operative association of said adjacently positioned follower members with said auxiliary guideway.

5. In combination with a plurality of hingedly connected door sections presenting a door structure, intermediate track follower members carried in the vicinity of the hinged portions of said sections, and guideways positioned at opposite sides of said door sections for accommodating said follower members, said guideways comprising upright, curved and horizontal sections, an auxiliary curved guideway of smaller curvature than and positioned outwardly from the first mentioned curved guideway section, a pair of adjacently positioned follower members carried at at least one margin of said door structure and adapted to be guided by and engage opposite sides of said auxiliary guideway, one of said follower members being shiftable within the first mentioned horizontal guideway section which guides the intermediate follower members, and means operable as an incident to the shifting of the door sections for controlling the operative association of said adjacently positioned follower members with said auxiliary guideway.

6. In combination with a plurality of hingedly connected door sections presenting a door structure, intermediate track follower members carried in the vicinity of the hinged portions of said sections, and guideways positioned at opposite sides of said door sections for accommodating said follower members, said guideways comprising upright, curved and horizontal sections, an auxiliary curved guideway of smaller curvature than the first mentioned curved guideway section and positioned outwardly thereof, and a pair of adjacently positioned follower members carried along one of the margins of said door structure and adapted to be guided by said auxiliary guideway, one of said follower members being positioned rearwardly and to one side of the other follower member, whereby to clear said first mentioned curved guideway section and thereby enable both of said adjacently positioned follower members to be received and guided by said auxiliary guideway.

7. In combination with a plurality of hingedly connected door sections presenting a door struc-

ture, intermediate track follower members carried in the vicinity of the hinged portions of said sections, and guideways positioned at opposite sides of said door sections for accommodating said follower members, said guideways comprising upright, curved and horizontal sections, an auxiliary curved guideway of smaller curvature than the first mentioned curved guideway section and positioned outwardly thereof, a pair of adjacently positioned follower members carried along one of the margins of said door structure and adapted to be guided by said auxiliary guideway, one of said follower members being positioned rearwardly and to one side of the other follower member, whereby to clear said first mentioned curved guideway section and thereby enable both of said adjacently positioned follower members to be received and guided by said auxiliary guideway, and switch means for controlling the direction of said adjacently positioned follower members into association with said auxiliary guideway.

8. In combination with a plurality of hingedly connected door sections presenting a door structure, intermediate track follower members carried in the vicinity of the hinged portions of said sections, and guideways positioned at opposite sides of said door sections for accommodating said follower members, said guideways comprising upright, curved and horizontal sections, an auxiliary curved guideway of smaller curvature than the first mentioned curved guideway section and positioned outwardly thereof, and a pair of adjacently positioned follower members carried along one of the margins of said door structure and adapted to be guided by said auxiliary guideway, one of said follower members being positioned rearwardly and to one side of the other follower member, whereby to clear said first mentioned curved guideway section and thereby enable both of said adjacently positioned follower members to be received and guided by said auxiliary guideway, said auxiliary guideway providing tread portions positioned side by side for accommodating said adjacently positioned follower members.

ALVIN V. ROWE.
